APPARATUS FOR CONTROLLING THE COURSE
OF A LATERAL BORE DEVIATING FROM
A VERTICAL WELL BORE
Filed April 19, 1951

UNITED STATES PATENT OFFICE

2,664,270

APPARATUS FOR CONTROLLING THE COURSE OF A LATERAL BORE DEVIATING FROM A VERTICAL WELL BORE

John A. Zublin, Los Angeles, Calif.

Application April 19, 1951, Serial No. 221,805

1 Claim. (Cl. 255—1.6)

1

The present invention relates specifically to apparatus for controlling the course of a curved bore deviating from an existing well bore. Since the issuance to me of U. S. Letters Patent 2,336,338 in 1943 there has been a considerable development in the field of drilling lateral bores deviating from existing vertical well bores and a number of improvements have been made in apparatus for that purpose, notable among which is the flexible drill pipe, inventions of my Patents 2,515,365 and 2,515,366.

More recently I have devised a combination drilling assembly embracing an outer normally curved flexible resilient drill guide, an inner rotatable nonresilient flexible tubular drive member and a bit driven by and rotatable with said drive member, all as more particularly defined in my copending application Serial No. 64,524.

Due to the fact that oil-bearing strata is often of quite well-defined and limited thickness, it is highly desirable to be able to control the course of a curved bore deviating from an existing well bore and it is the purpose and object of the present invention to provide apparatus for minimizing the tendency of the drill bit to leave the desired path during the drilling of a deviating bore.

More specifically, the present invention has as its purpose the object of provision of an apparatus by which certain gravitational and other forces whose effect would be to cause the drill guide to sag and bring about unwanted departure of the bit from the prescribed course of the deviating bore are directly absorbed by the wall of the deviating bore being drilled and so neutralized as to avoid unwanted deflection of the drill bit. Further and more detailed objects of the invention will become apparent as the description proceeds, which will be given by reference to the accompanying drawings, in which

Figure 1 is a side elevational view with parts broken away for clearness, showing the operating portion of the apparatus inserted in a well bore and with the initiation of the drilling of a curved bore and embodying a diagrammatic illustration of the advantages attained thereby.

Figure 2 is a cross-sectional view on line 2—2 of Figure 1 showing only the outer flexible resilient normally curved drill guide.

Figure 3 is a cross-sectional view similar to Figure 2 of a modified form of the invention.

Figure 4 is a cross-sectional view similar to Figure 2 of a second modified form of the invention and

Figure 5 is a cross-sectional view similar to Figure 2 of still another form of the invention.

Referring to Figure 1, the vertical well bore is indicated at 10 and the deviating curved bore is indicated at 11. The apparatus illustrated in this figure embraces the outer resilient normally curved flexible drill guide 12 which may take the form of and be constructed similar to the teachings of my U. S. Patent 2,515,365 issued July 18, 1950. However, I prefer to employ about seven of the dovetailed teeth 13 per complete revolution of the drill guide 12 with a pitch of the slot 14 of about twice the diameter of the guide 12, that is, for a drill guide of 4½ inch diameter longitudinal spacing of the convolutions of the slot 14 lengthwise of the guide 12 will be about nine inches.

Mounted interiorly of the guide 12 for rotation therein is the nonresilient flexible drill bit drive member 15. This flexible drill bit drive member 15 is adapted to be connected into the drill string which extends to the surface of the well to be rotated thereby. The flexible nonresilient drill bit drive member 15 extends downwardly through the normally curved resilient drill guide 12 and carries at its lower end for rotation therewith the drill bit body 16 having the rollers 17. The drill bit body 16 may conveniently be constructed pursuant to the teachings of my copending application Ser. No. 219,266 filed April 4, 1951, now Patent No. 2,631,820.

The arrangement is such that the bit embracing the bit body 16 and the rollers 17 is positively driven through rotation of the flexible drill bit drive member 15. The normally curved flexible resilient drill guide 12 which is frictionally held against rotation imposes a sideward pressure on the bit causing the same to deviate from the vertical bore 10. A typical flexible resilient drill guide such as represented at 12 will have an over-all length of approximately 16 feet and its curvature may be on a radius of approximately 16 feet.

It will be observed that the cutting face presented by the rollers 17 has a diameter greater than the diameter of the flexible resilient normally curved drill guide 12. The difference in the diameter of the cutting face of the bit and that of the flexible resilient drill guide 12 is represented at a in Figure 1. This is an essential feature of this form of apparatus because it is necessary that the circulating drill fluid employed in the rotary drilling operation pass upwardly in the annular space between the wall of the curved bore being drilled and the flexible normally curved drill guide 12.

I have found that this necessary clearance be-

tween the diameter of the normally curved flexible resilient drill guide such as 12 and the wall of the curved deviating bore such as 11 permits gravitational and other torsional and weight forces to cause the free end of the apparatus and notably the bit itself to sag downwardly and thus to progressively cut away the lower wall of the curved bore being drilled with the result that unless the effect of these forces is compensated for in some manner, the drill bit will follow a path yielding a bore of the general configuration represented by the dot and dash lines 18 of Figure 1 rather than a true continuation of the curved bore 11 as indicated at 19 in Figure 1. Furthermore, progress of the bit has been found to be in the manner illustrated by the varying distances $b-d$ and $b'-d'$ in Figure 1. Specifically, the bit, at the time that gravitational force is imposed upon it because of its generally horizontally extending position, will proceed downwardly at a rather sharp inclination until the outer wall of the drill guide such as 12 rests upon the lower wall of the curved bore, such as 11, being drilled. As soon as the surface of the drill guide such as 12 is supported by the wall of the curved bore, the bit will no longer sag until it has progressed to a point where gravitational and other forces again exert themselves. The first declination is illustrated by the space b nearest the rollers 17 of the bit in Figure 1. The second space during which the bit is in reality supported against gravitational forces by contact of the drill guide with the wall of the curved bore is represented by the next juxtaposed space designated d . The action is repetitious and aggravated as indicated by the spaces indicated b' and d' in Figure 1.

This tendency of the bit to be thrown off its course by gravitational, torsional and other forces has been affirmatively established by surveying instruments and has been found to give an undesired result in that it may well result in the deviating bore missing that area of the producing field strata which it is most desired to penetrate.

To overcome the effect of such gravitational, torsional and other forces on the apparatus, I have provided at the lower end of the normally curved flexible drill guide 12 laterally projecting elongated skids or shoes designated 20 in Figure 1 and circumferentially spaced about the outer surface of the normally curved flexible drill guide 12. In the preferred embodiment shown in Figure 1 there are three of the skids or shoes 20 as will be seen by reference to Figure 2. The shoes or skids 20 bear against the surface of the curved bore 11 and act as supports for the apparatus in such manner that they absorb the gravitational, torsional and other forces that would otherwise cause the bit to be thrown off the desired course.

By virtue of the circumferential spacing of the skids or shoes 20 ample clear space is provided therebetween to facilitate the flow of the circulating drilling fluid during normal rotary drilling operations. Inasmuch as the gravitational, torsional and other forces are rendered ineffective to deflect the bit, it will progress along the true predetermined course indicated at 19 in Figure 1.

The normal, unstressed, curved configuration of drill guide 12 is such that when inserted into the vertical well bore 10 it exerts its greatest pressure against the side of the vertical bore 10 from which the lateral bore 11 takes off. This pressure tends to impel the bit and the rib 20

away from the vertical bore 10 and insures that the rib 20 provided at the inclined lower end will slide into the curved deviating bore 11 without being caught on the ledge at the point of take-off of the curved bore 11 and the vertical bore 10. The inner, rotatable drive member 13, while free to rotate within the normally curved, flexible resilient drill guide 12, is not free to partake of any substantial relative longitudinal movement there-through. The specific mountings for the inner rotatable drive member 15 within the normally curved, flexible drill guide 12 form no necessary specific part of the present invention and the details have not been delineated in the drawings.

In Figure 3 I have illustrated a slight modification in which the skids or shoes are designated as 21 and in this instance are symmetrically spaced 90° apart around the circumference of the normally curved flexible drill guide 12. In this way the bit is compelled to travel in precisely the predetermined curved path established for it, whereas in the preferred embodiment of Figures 1 and 2 there is no limitation on the tendency of the bit to move upwardly in compliance with the force exerted by the normally curved flexible drill guide 12.

In the modification of Figure 4 the skids or shoes 22 are of greater thickness than the distance represented at a in Figure 1. It will be recalled that this distance represents the difference between the diameter of the cutting face of the bit and the diameter of the normally curved flexible drill guide 12. In the form of the invention represented in Figures 1 to 3, the skids or shoes have a thickness approximating the distance a . In the form of the invention illustrated in Figure 4 it is possible, through the employment of skids 22 of greater thickness than the distance a to cause the bit to partake of a greater upward component of movement than would be imparted thereto by the normal forces of the curved flexible drill guide 12. Indeed, in the modification of Figure 4 this further component is indicated by the small reference character x so that the thickness of the skids or shoes 22 in Figure 4 as is indicated thereon represents a distance equal to a plus x . In this case, not only are the gravitational and torsional forces neutralized but a positive component is imparted tending to compel the bit to follow a course giving a curved bore a minimum radius.

It will be appreciated that the skids or shoes 22 of Figure 4 may be located at any predetermined point about the circumference of the drill guide to compensate for the torsional forces which would otherwise tend to change the course of the bit and the azimuth of the deviating bore. It will thus be seen that the skids 22 can be arranged in such a manner that the component resulting from gravitational and torsional forces combined will direct the bit in the desired direction.

In the modification of Figure 5 a single skid or shoe 23 is shown as carried by the lower portion of the external surface of the normally curved flexible drill guide 12 so that the bit is free to act in response to torsional and other forces in directions other than a downward direction. Since the oil-producing strata lies in a horizontal plane, the deflections of the bit laterally may not, in some cases, be particularly objectionable and in the form of the invention shown in Figure 5 such lateral deflections may occur. In all instances it will be observed that positive means are provided for supporting the ap-

paratus as it assumes a horizontally projecting position from the inner surface of the bore being drilled, thus minimizing the effect of those forces that tend to draw the bit off its predetermined course.

Having thus described my invention, what I claim is:

Apparatus for drilling a curved bore deviating from an existing vertical well bore comprising in combination, an outer normally curved 10 nonrotatable flexible resilient drill guide, an inner flexible drive member mounted for rotation within said drill guide, a drill bit carried at the lower end of and rotatable with said flexible drive member, said bit having a cutting face of greater 15 diameter than the diameter of said drill guide, and projections carried on said drill guide at the lower end thereof having greater radial thick-

ness than represented by the difference in the diameter of said drill guide and said cutting face and positioned about the circumference of said guide so as to transmit gravitational and other forces to the wall of the bore being drilled and thereby impel the bit in a direction opposed to the resultant component of such forces.
